US0D1084023S

(12) **United States Design Patent** (10) Patent No.: **US D1,084,023 S**
 Dellinger et al. (45) Date of Patent: ** Jul. 15, 2025

(54) **DISPLAY SCREEN OR PORTION THEREOF WITH GRAPHICAL USER INTERFACE**

(71) Applicant: **Apple Inc.**, Cupertino, CA (US)

(72) Inventors: **Richard R. Dellinger**, San Jose, CA (US); **David C. Graham**, Campbell, CA (US); **Vincent M. Lane**, San Francisco, CA (US); **Meredith Anne Ross**, San Francisco, CA (US); **Raymond Sepulveda**, Portland, OR (US)

(73) Assignee: **Apple Inc.**, Cupertino, CA (US)

(**) Term: **15 Years**

(21) Appl. No.: **29/940,362**

(22) Filed: **May 1, 2024**

Related U.S. Application Data

(63) Continuation of application No. 29/863,653, filed on Dec. 21, 2022, now Pat. No. Des. 1,041,505, which is a continuation of application No. 29/739,617, filed on Jun. 26, 2020, now Pat. No. Des. 975,719.

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing the claimed design.

The peripheral dashed broken lines depict a display screen or portion thereof, and form no part of the claimed design.
